UNITED STATES PATENT OFFICE.

HENRY M. ROSENDAL DAM, OF BROOKLYN, NEW YORK, ASSIGNOR TO NOMA ELECTRIC CORPORATION, OF NEW YORK, N. Y., A CORPORATION OF NEW YORK.

DESIGN FOR A CHRISTMAS DECORATIVE LIGHTING FIXTURE.

Application filed March 12, 1927. Serial No. 21,115. Term of patent 14 years.

To all whom it may concern:

Be it known that I, HENRY M. ROSENDAL DAM, a citizen of Denmark, residing in Brooklyn, Kings County, New York, have invented a new, original, and ornamental Design for a Christmas Decorative Lighting Fixture, of which the following is a specification, reference being had to the accompanying drawing, forming part thereof.

Fig. 1 is a view in elevation of a Christmas decorative lighting fixture showing my new design.

Fig. 2 is a top plan view thereof.

I claim:

The ornamental design for a Christmas decorative lighting fixture, as shown.

HENRY M. ROSENDAL DAM.
